SPOON OR SIMILAR ARTICLE

William H. Gerth, New York, N. Y., assignor to Oneida Ltd., Oneida, N. Y., a corporation of New York

Application December 17, 1954, Serial No. 33,596

Term of patent 14 years

(Cl. D54—12)

Fig. 7

Fig. 5

Fig. 1 is a front view of a spoon showing my new design, the dominant features residing in the portions shown in full lines;

Fig. 2 is a back view of the spoon;

Figs. 3, 4 and 5 are sections taken on the respective lines 3—3, 4—4 and 5—5 of Fig. 1;

Fig. 6 is a side elevational view of the spoon; and

Fig. 7 is a fragmentary view on an enlarged scale showing the ornamental detail near the top of the handle.

I claim:

The ornamental design for a spoon or similar article, substantially as shown and described.
